METHOD AND APPARATUS FOR CLEANING SPINNING DEVICES FOR THE MANUFACTURE OF ARTIFICIAL THREADS.

Application filed April 8, 1924, Serial No. 705,138, and in Germany October 7, 1923.

During the spinning of artificial silk from copper oxide ammonia cellulose solutions, copper hydroxide deposits are separated off in the spinning device, more particularly at 5 the outflow pipe of the spinning nozzle. These deposits offer a resistance to the bunch of threads drawn through, which may easily cause threads to break. Hitherto it has been necessary temporarily to stop the machine 10 or at least the separate spinning devices in order to clean the pipe.

According to the invention this cleaning may be effected during working without it being necessary to interrupt the spinning 15 operation and consequently break the thread. A cleaning fluid is caused to flow at a suitable point into the spinning nozzle or at the tapered lower outlet of the same, which fluid dissolves the copper hydroxide. A 20 suitable cleaning fluid is a dilute acid, for instance sulphuric acid of 10%. This fluid enters at a pressure slightly exceeding that of the precipitating fluid in the spinning device.

25 A spinning device suitable for carrying out the cleaning method just described may be constructed in such a manner that the spinning nozzle is connected by a separate pipe at a suitable point to the vessel for the cleaning fluid. The requisite excess pressure 30 of the cleaning fluid may be obtained by placing the said vessel in an elevated position. It may also be obtained by raising the vessel only for the period, during which the 35 cleaning fluid is to flow through. This renders cocks in the supply pipe superfluous. The vessel may on the other hand be placed so low that only as much fluid can be withdrawn at a time as has been poured into 40 the vessel above a certain level.

If a deposit is only formed at the bottom 45 of the outlet of the spinning nozzle, it is sufficient to introduce the cleaning fluid at the bottom. If, however, there is a deposit 50 higher up, the cleaning fluid would be economized by connecting the supply pipe somewhat higher, so that the cleaning fluid must not first be driven upwards in counter-flow, but can simply flow downwards through the 55 nozzle.

In the accompanying drawing five con-

structional examples of the invention are shown.

T is the entire spinning device, e the 55 conical nozzle, t the outflow pipe of the nozzle and w the supply vessel for the precipitating fluid, which is connected by suction pipes S to the separate spinning devices. The precipitating fluid flows through the outlet pipe t at a velocity, which corresponds 60 to the difference in pressure between the outflow opening of t and the level of the liquid in the vessel w. Above the place where the copper hydroxide is deposited a lateral pipe a is provided, which supplies 65 cleaning fluid, for instance 10% sulphuric acid, from a vessel b.

Various ways may be adopted for using 70 the vessel b and for connecting it to the spinning nozzle e or the outlet t of the same:

(1) The acid is in a vessel b, Fig. 1, which is located at about the level of the upper edge of the spinning nozzle. At h is a cock, 75 which is kept open until the copper deposit has been dissolved.

(2) The acid vessel b, Fig. 2 is placed so 80 low that the level of the fluid is the same as the level in the vessel w. In this case no acid flows through the pipe a. If the pipe a be made flexible and the vessel b be somewhat raised, so that the level of the acid contained 85 therein is above the level in the vessel w, acid will flow down through a as long as there is a difference in the level. When the copper deposited is dissolved, the vessel b is lowered again to its old position and the flow of acid will cease. A cock for stopping 90 the flow of the acid is in this case superfluous.

(3) A vessel b, Fig. 3, is fixed in such a 95 manner that, when about half full of acid, the level of the fluid is the same as the level in the vessel w. On more acid being caused to flow into the vessel b from a reservoir, the said acid will at once flow through a, as the level in b is raised, owing to the addition of fresh acid. As soon as no more acid is added, the level in b immediately assumes the same level as that in w and the flow of acid ceases.

(4) The cleaning fluid flows in as in Fig. 100 1 through the pipe a, which is provided with

a cock *h*, Fig. 4. The pipe *a* is introduced laterally into the pipe *s*, which enters above the tapered part *e* of the nozzle. This pipe can of course be connected at any other point of the nozzle. On the cock *h* being opened the cleaning fluid will flow in, will mix with the precipitating fluid and will effectively seep over all those parts of the nozzle, on which deposits are liable to be formed.

(5) The spinning device shown in Fig. 5 shows a tapered nozzle within a cylindrical part *F*. The precipitating fluid enters through a pipe *a* at the bottom of the cylindrical part, rises in the latter and falls into the tapered part *e*. This spinning device has already been described, for instance in German Patent 220,051. In this case the cleaning fluid is supplied through a pipe *a* having a cock *h* in such a manner that the two fluids are already mixed before entering the spinning device. In this case as well the pipe may be connected elsewhere.

When the entire tapered part of the nozzle is to be cleaned, it is necessary in the arrangements shown in Figs. 4 and 5 to interrupt the spinning operation during the cleaning period, which causes the threads to break. This, however, lasts for one minute at the most and causes no appreciable harm.

In the constructional example shown in Figs. 4 and 5 cleaning fluid is economized when the entire nozzle is to be cleaned.

35 A further advantage is that the cleaning operation is carried out more rapidly.

What we claim is:—

1. That method of cleaning spinning devices employed in the manufacture of artificial silk threads without necessarily interrupting the passage of the threads through said device which consists in introducing into the spinning device and into the setting fluid passing therethrough, a fluid capable of dissolving deposits formed in

the spinning device; and allowing such intermingled fluids to pass outwardly from the spinning device.

2. That method of cleaning spinning devices employed in the manufacture of artificial silk threads from copper oxide ammonia cellulose solutions without necessarily interrupting the passage of the threads through said device, which consists in introducing sulphuric acid into the spinning device while precipitating fluid is flowing therethrough.

3. That method of cleaning spinning devices employed in the manufacture of artificial silk threads from copper oxide ammonia cellulose solutions without necessarily interrupting the passage of the threads through said device, which consists in introducing dilute sulphuric acid into the spinning device while precipitating fluid is flowing therethrough.

4. That method of freeing deposited copper hydroxide from spinning devices employed in the manufacture of artificial silk threads from copper oxide ammonia cellulose solutions which consists in introducing into the spinning device while precipitating fluid is flowing therethrough an acid capable of attacking and removing the copper hydroxide from the spinning device.

5. In a spinning apparatus for the manufacture of artificial silk threads; the combination of a spinning nozzle; means for introducing a setting fluid for the threads into said nozzle; a vessel located exteriorly of the nozzle and adapted to contain a cleaning fluid; and a flexible pipe connecting said vessel with the spinning nozzle whereby when the vessel is elevated liquid may flow from said vessel into the nozzle and when lowered such flow will be cut off.

In testimony whereof we have signed our names to this specification.

EMIL ELSAESER.
HUBERT KEMPF.
